US00D458728S

(12) United States Design Patent (10) Patent No.: US D458,728 S
 Funk et al. (45) Date of Patent:  Jun. 18, 2002

(54) CEREAL BAR HAVING A CEREAL PIECE INCLUDED THEREON

(75) Inventors: Dean F. Funk, Brooklyn Park; Robert J. Harrison, Champlin; Dena K. Strehlow, Maple Grove, all of MN (US)

(73) Assignee: General Mills, Inc., Minneapolis, MN (US)

() Term: 14 Years

(21) Appl. No.: 29/111,593

(22) Filed: Sep. 30, 1999

(51) LOC (7) Cl. 01-01

(52) U.S. Cl. D1/101

(58) Field of Search D1/100, 101, 116-130, D1/199; 426/94, 104, 439, 440, 445, 446, 449, 450, 458, 559
